[57] ABSTRACT

The device includes two elongated flat members that can be fully telescoped together when the device is not in use and extended when it is to be used. Resilient clips at the spaced ends of the telescopically received members hold the device in place on any conventional toilet seat for use by small children.

DETACHABLE DEVICE FOR PARTIALLY SUPPORTING A SMALL CHILD ON A CONVENTIONAL TOILET SEAT

BACKGROUND OF THE INVENTION

1. Field of the Invention

This invention relates generally to toilet seats, and pertains more particularly to a detachable device for use on a toilet seat for supporting a small child.

2. Description of the Prior Art

The prior art is replete with various contrivances for supporting small children when using a toilet. Some are in the form of small chairs that are simply superimposed upon the conventional seat. These have the basic shortcoming of occupying a considerable amount of space, and their use by parents traveling with small children pose obvious problems. Flexible attachments, usually of cloth or canvas, have been devised but these cannot readily be cleaned after each use. Resort has even been made to disposable toilet seats for use by infants, but these seats can prove to be quite costly and also have the drawback of taking up space, particularly if any number is taken along on a trip.

Other devices with which I am acquainted require that parts be permanently attached either to a conventional toilet seat or the seat modified sufficiently so as to permit a given attachment to be used therewith. Quite obviously, those requiring modification of the seat itself cannot be carried from place to place.

SUMMARY OF THE INVENTION

Accordingly, one object of the present invention is to provide a device for use by small children in association with a conventional toilet seat, the device being adjustable to fit any normal toilet seat.

Another object is to provide a device of the foregoing character that will accommodate children of various ages and sizes.

Another object is to provide a detachable device for toilet seats that will be firmly held and not readily shift when being used, yet which can be quickly detached when not needed.

Still another object of the invention is to provide a device that can be collapsed or telescoped to permit it to be carried from place to place while traveling. In this respect, the invention has for an aim the provision of a device that will be lightweight as well as compact.

Still further, the invention has for an object the provision of a device of this type that is hygienically satisfactory, being easily wiped clean after each use.

Further, the invention has for an object the provision of a device that will be inexpensive to manufacture, thereby encouraging its widespread use.

Still another object is to provide a device for use by small children that requires no modification of the conventional seat or any portion of the toilet. More specifically, an aim of the invention is to obviate the need for any permanent fasteners, my device being completely portable.

Another object of the invention is to provide a device that will not damage or mar any surfaces, either those associated with the usual toilet or those apt to be encountered when the device is not being used.

Briefly, my invention includes a pair of telescopically mated members. One elongated member, being tubular, has a rectangular passage extending inwardly from

one end thereof which slidably receives a second elongated member constituting a rectangular strip. In this way, when the device is not needed, the strip can be moved inwardly so that it is fully received within the tubular member, thereby enabling the device to be readily carried from place to place. There is a resilient clip at each outer end of the two elongated members, each clip having a pad of compressible material mounted thereon. Hence, the clips can be sprung so as to resiliently engage the sides of the toilet seat or preferably the sides of the bowl rim when being used. The clips prevent inadvertent shifting of the device from the specific location where it is placed, thereby enabling the device to be located so as to very the size of seat opening in order to accommodate children of various ages. When not being used, the resilient clips assume a confronting relationship with the tubular elongated member, thereby permitting the device to be carried in a traveler's luggage or conveniently place within an automobile, such as under the vehicle's front seat.

BRIEF DESCRIPTION OF THE DRAWINGS

FIG. 1 is a perspective view of a toilet with my device straddling the seat thereof;

FIG. 2 is a sectional view taken in the direction of line 2—2 of FIG. 1;

FIG. 3 is a perspective view of my device as it appears in FIG. 1 but with the toilet seat deleted;

FIG. 4 is a sectional view taken in the direction of line 4—4 of FIG. 2;

FIG. 5 is a perspective detail showing one way in which the resilient clip at the left may be anchored to the elongated member at the left, and

FIG. 6 is a sectional view corresponding generally to FIG. 2 but with my device collapsed so that it can be stored.

DESCRIPTION OF THE PREFERRED EMBODIMENT

Referring first to FIG. 1, a typical toilet has been pictured in its entirety, the toilet having been given the reference numeral 10. Although the parts of the toilet 10 are conventional and well known, it will be helpful, it is believed, in appreciating the benefits to be derived from a practicing of my invention to identify the various portions of the toilet in greater detail. Therefore, the toilet bowl has been labeled 12 having a rim 14 at its upper edge. The usual tank has been assigned the reference numeral 16. The lid for the toilet carries the reference numeral 18 and cooperates with the seat 20 to close the opening 22 in the seat. At this stage, it will be appreciated that the rim 14 and the seat 20 will vary in width from manufacturer to manufacturer.

My device has been designated generally by the reference numeral 30. It is comprised of two elongated members 32 and 34. These members 32, 34 can be fabricated from a suitable plastic, such as rigid polyvinyl chloride, high density polyethylene, polypropylene or nylon. Actually, one of the advantages of my invention is that it can be fabricated from a number of plastic materials, depending in large measure upon the equipment available for molding or extruding and also enabling the manufacturer to select the most economical plastic materials for a desired commercial embodiment of my device 30.

Describing the elongated member 32, it will be recognized that in the form illustrated it constitutes a rect-

angular tube 36 having flat upper and lower surfaces. In this regard, it has a rectangular passage 38 extending inwardly from the right end 40. When so fabricated, the member 32 can be extruded, the extrusion providing the passage 38.

Assuming that the extrusion technique has been adopted, then the passage 38 initially extends completely from the right end 40 to the left end. However, in use, the left end is to be held in place with respect to the toilet seat 20. Although discernible to a degree from FIG. 4, it is believed more readily understandable from FIG. 5 that a plastic strip or insert 42 is provided having a slot at 44, which can be cut with a saw. Secured within the slot 44 is one end of a resilient clip 46 in the form of a strip of spring steel that is normally biased into a U-shaped configuration as seen in FIG. 6. A pad 48 of sponge rubber or foamed plastic is adhered to the free end of the resilient strip or clip 46.

The cross section of the insert 42 corresponds to that of the passage 38 so as to preferably be snugly received or press fitted into the left end of the rectangular passage 38. The insert 42 can be fixedly retained in the left end of the passage 38 by an appropriate adhesive. However, when thermoplastic materials are utilized for the members 32, 42, the two can be secured together by conventional heat sealing techniques.

Turning now to a description of the member 34, it will be perceived that it constitutes a single strip 50 having a rectangular cross section commensurate with that of the passage 38. It will be understood that the members 32, 34 are telescopically mated and that the strip 50 must slide within the passage 38.

Actually, the strip 50 can have the same cross section as the insert 42. Consequently, when fabricating the strip 50, only a single extrusion die need be utilized to produce a continuous strip that can be cut to form individual strips 50 and inserts 42 of the proper lengths in the making of a number of devices 30.

Corresponding generally to the slot 44 in the insert 42 is a slot 52 in the right end of the strip 50. As with the slot 44, the slot 52 receives therein one end portion of a resilient clip or strip 54, such as spring steel as mentioned when describing the clip 46. Still further, a pad 56 is mounted on the clip 54 in the same fashion as is the pad 48.

With the preceding information in mind, it is believed that the manner in which my device 30 is employed is readily understandable. When carried, it is collapsed as illustrated in FIG. 6. From FIG. 6 it will be apparent that the resilient clips 54 assume a U-shaped relationship with their respective members 32 and 34, the pads 48, 56 then confronting the underside of the tubular member 32. The strips or clips 46, 54 can be of fairly thin stock in that a large amount of resiliency is not necessary.

However, when the device 30 is to be attached to a conventional toilet seat, such as the seat 20, the member 34 is extended or pulled from its mated relationship with the member 32 as depicted in FIG. 6, there being only a sliding fit between these two members. Depending upon the width of the toilet seat 20, the degree of extension is determined in accordance with the particular width toilet seat that is encountered. The clips 46 and 54 are simply flexed downwardly so as to cause the pads 48 and 56 to pressurally bear against the rim 14. In some instances, the pads 48, 56 will press against the outside side edges of the toilet seat.

Depending upon the size of the infant to be accommodated, the device 30 can be shifted either forwardly or rearwardly from a midway position. More specifically, if the child is quite small, then the device will be positioned closer to the front of the seat 20; on the other hand, if the child is relatively large, then the device 30 will be moved rearwardly. It will be appreciated that the resilient clips 46, 54 hold the device 30 in any selected position that is best for the particular child.

10 The child receives some support from the forward part of the seat 20. However, the flat upper surfaces formed on the members 36 and 50 underlie the buttocks of the child and provide comfortable support at the rear.

When the device 30 is not needed, it is again collapsed into the compact form in which it appears in FIG. 6. It can then be conveniently carried, particularly when traveling, so that it is in immediate readiness for subsequent use. Its stick-like flatness, as illustrated in FIG. 6, renders my device sufficiently thin so that it can be stowed without difficulty under the front seat of an automobile.

Consequently, not only can the device 30 be extended to fit any width of toilet seat that might be encountered when traveling, but it will accommodate 25 children of different ages. Further, it will be understood that my device 30 can be easily wiped clean, thereby enabling a high degree of sanitation to be maintained which is important when traveling.

1. A detachable device for partially supporting a 30 small child on a conventional toilet seat or toilet bowl comprising a first elongated member having a flat upper surface and a rectangular passage extending inwardly from one end to a location near the other end thereof, a second elongated member having a flat upper surface and a cross section corresponding substantially to that of said passage so that one end of said second member can be telescopically received within said passage, and respective means at the said other ends of said elongated member for engaging the opposite sides of a conventional toilet seat or the underlying toilet bowl to maintain said first and second elongated members at substantially the same elevation as the upper surface of said seat or the upper surface of the toilet bowl, said engaging means including a resilient clip at each outer end of said elongated members, whereby said members can be relatively extended from their telescopically received relation to a length sufficient to span the opening of the toilet seat or bowl for the partial support of a child at said substantially same elevation as the said upper surfaces of said seat or bowl.

2. A detachable device in accordance with claim 1 in which the length of said passage is substantially equal to the length of said second member so that said one end of said second member can be positioned adjacent the end of the passage near said one end of the first member with the consequence that the other end of said second member projects only slightly from said passage.

3. A detachable device in accordance with claim 2 in which said members are of plastic material.

4. A detachable device in accordance with claim 1 in which said resilient clips are in the form of strips biased in a direction to confront said first member when said second member is telescoped within said first member.

5. A detachable device in accordance with claim 4 including a pad attached to the confronting sides of said strips.

6. A detachable device in accordance with claim 5 in which said strips are of spring steel.

7. A detachable device in accordance with claim 6 in which said elongated members are of plastic material and end portions of said strips opposite said pads are anchored in the said other ends of said members.

8. A detachable device for partially supporting a small child on a conventional seat or bowl of a toilet comprising a pair of telescopically mated relatively rigid strip members, one of said members being slidably received within the other, and a second pair of thinner relatively flexible strip members having first end portions fixedly anchored within the opposite end portions of said first members, the first end portions of said second members extending in the general plane of said first members and said second members having second

end portions extending downwardly from said first end portions so as to resiliently engage the opposite sides of a conventional toilet seat or toilet bowl when said first members are extended to a length such as to have said opposite end portions thereof supported on the upper surface of the toilet seat or on the upper surface of the toilet bowl, said second end portions then engaging the opposite sides of the seat or bowl to maintain said first members in a spanning relation with the opening of said seat or bowl for the partial support of a child at the proper elevation for using the toilet.

9. A detachable device in accordance with claim 8 in which said first strip members are of plastic and said second members are of spring steel.
